US0D1025097S

(12) **United States Design Patent** (10) Patent No.: **US D1,025,097 S**
(45) Date of Patent: ** Apr. 30, 2024

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Prashant Chaturvedi**, Allentown, PA
(US); **Rhythm Agarwal**, Bethlehem,
PA (US); **Karelys Alfonzo**,
Coopersburg, PA (US); **Gregory
Altonen**, Easton, PA (US); **Brad
Michael Kreschollek**, Bethlehem, PA
(US); **Shenchi Tian**, Easton, PA (US)

(73) Assignee: **Lutron Technology Company LLC**,
Coopersburg, PA (US)

(**) Term: **15 Years**

(21) Appl. No.: **29/837,838**

(22) Filed: **May 9, 2022**

Related U.S. Application Data

(63) Continuation of application No. 29/769,339, filed on
Feb. 4, 2021, now Pat. No. Des. 955,411, which is a
continuation of application No. 29/699,638, filed on
Jul. 26, 2019, now Pat. No. Des. 910,660.

(57) **CLAIM**

The ornamental design for a display screen or portion thereof with graphical user interface, as shown and described.

DESCRIPTION

The file of this patent contains at least one drawing photograph executed in color. Copies of this patent with color drawin(s) photograph(s) will be provided by the Office upon request and payment of the necessary fee.

The sole FIGURE shows a display screen or portion thereof with graphical user interface showing our new design. The peripheral dashed broken lines illustrate a display screen or portion thereof, and form to part of the claimed design.

**1 Claim, 1 Drawing Sheet
(1 of 1 Drawing Sheet(s) Filed in Color)**
